Des. 184,973
Patented Apr. 28, 1959

184,973

HOLDER FOR A DRINKING GLASS OR THE LIKE

Joseph N. Amigone, Buffalo, N.Y.

Application September 5, 1957, Serial No. 47,616

Term of patent 14 years

(Cl. D4—3)

Fig. 1 is a front elevational view of a holder for a drinking glass or the like, showing my new design;

Fig. 2 is a side elevational view thereof; and

Fig. 3 is a top plan view thereof.

I claim:

The ornamental design for a holder for a drinking glass or the like, substantially as shown.
